US00D884518S

(12) **United States Design Patent** (10) **Patent No.:** **US D884,518 S**
(45) **Date of Patent:** **** May 19, 2020**

(54) **CONNECTED DEVICE**

(71) Applicant: **The Nielsen Company (US), LLC**,
New York, NY (US)

(72) Inventors: **Timothy Scott Cooper**, Oldsmar, FL
(US); **Saso Vranek**, Ilirska Bistrica
(SI); **Michael Alan Hicks**, Clearwater,
FL (US); **James Joseph Vitt**, Palm
Harbor, FL (US)

(73) Assignee: **The Nielsen Company (US), LLC**,
New York, NY (US)

(**) Term: **15 Years**

(21) Appl. No.: **29/710,996**

(22) Filed: **Oct. 28, 2019**

Related U.S. Application Data

(63) Continuation of application No. 29/623,974, filed on
Oct. 27, 2017, now Pat. No. Des. 864,770.

CLAIM

The ornamental design for a connected device, as shown and
described.

DESCRIPTION

FIG. 1 is a front, right perspective view of a connected device.

FIG. 2 is a front view of the connected device of FIG. 1.

FIG. 3 is a rear view of the connected device of FIG. 1.

FIG. 4 is a right side view of the connected device of FIG. 1.

FIG. 5 is left side view of the connected device of FIG. 1.
FIG. 6 is a top view of the connected device of FIG. 1; and,
FIG. 7 is a bottom view of the connected device of FIG. 1.
The features shown in broken lines form no part of the
claimed design.

1 Claim, 3 Drawing Sheets
